CLAIM

The ornamental design for a headband for ear protection, as shown and described.

DESCRIPTION

FIG. 1 is a front perspective view of a headband for ear protection according to my new invention;

FIG. 2 is a front elevational view thereof;

FIG. 3 is a back elevational view thereof;

FIG. 4 is a side elevational view thereof, the opposite side being a mirror image;

FIG. 5 is a bottom plan view thereof; and,

FIG. 6 is a top plan view thereof.

The broken lines shown in all figures are for illustrative purpose only, and form no part of the claimed design.
